APPARATUS FOR MANUFACTURING
THREAD OR THE LIKE

Lavern J. Jordan, Fairview Village, Ohio, assignor
to Industrial Rayon Corporation, Cleveland,
Ohio, a corporation of Delaware

Application October 17, 1938, Serial No. 235,375

6 Claims. (Cl. 242—53)

This invention relates to apparatus for handling threads, filaments, bands, ribbons or the like, hereinafter called "thread or the like." More particularly, the invention pertains to apparatus applicable to the manufacture of thread or the like of synthetic origin pursuant to a method in which the thread or the like is precipitated in a coagulating medium. The invention is especially applicable to the production of extrusion products manufactured according to any process, such as the viscose, casein, cuprammonium, cellulose acetate or nitrocellulose process, in which a coagulating bath is or can be used. Multiple filament artificial silk thread, staple fiber, artificial horsehair, artificial straw and similar products requiring long periods of immersion in the coagulating bath to insure coagulation of the innermost portions thereof are examples of materials to the manufacture of which the invention is applicable.

By way of illustration, but in no sense of limitation, the invention will be described in connection with the manufacture of multiple filament artificial silk thread produced according to the viscose process. In this process, as in all processes by which artificial silk thread is produced by a wet method, the mass of material from which the thread is formed is extruded into a suitable bath wherein the thread is coagulated. If the thread is being produced in the conventional manner; i. e., according to either the spool-spinning system or the pot-spinning system, the thread, after passing through the coagulating bath, is collected in suitable package form either on a rotating spool or in a rapidly rotating centrifuge.

In producing artificial silk thread, it is the usual practice to withdraw the thread from the coagulating bath at a speed of from 60 to 80 meters per minute. Since for various reasons, as, for example, operating convenience, structural limitations, etc., the bath is relatively shallow, the depth of immersion of the spinneret below the surface is small and the time of immersion of the thread is correspondingly short. As a result, the thread is often imperfectly coagulated when it leaves the bath. Imperfect coagulation gives rise to variations in such physical properties as tensile strength, luster, dyeing qualities, etc., all of which are objectionable.

It has been known heretofore that beneficial results with regard to the physical properties of the thread, especially the dyeing qualities, can be obtained by exposing the thread to the coagulating bath for a period long enough to insure sub-

stantially complete coagulation thereof. To that end, numerous attempts have been made in the past to increase the period of immersion of the thread by slightly increasing the length of travel of the thread in the bath. Attempts to increase the thread travel in the bath have generally consisted of arrangements of guides or the like over which the thread has been drawn before leaving the bath.

These arrangements have, however, met with little success because of excessive tensions imposed on the thread, difficulties in starting the thread through the guides, etc. Among other things, the use of such guides is rendered difficult by the space in the bath trough allowed by constructional limitations. To provide a long coagulating period for the thread or the like in a comparatively small space by continuously storing a relatively long length thereof in or in contact with the coagulating bath, preferably in the form of an advancing generally circular helix, is one of the objects of the instant invention.

Other objects of the invention in part are obvious and in part will appear more in detail hereafter.

In the drawing, which illustrates one embodiment of the invention, Figure 1 is a sectional elevation, from line 1—1 of Figure 2, of a conventional spool-spinning apparatus equipped with the apparatus of the invention, parts being broken away to reveal constructional details; Figure 2 is an elevation of the same apparatus from line 2—2 of Figure 1; Figure 3 is a sectional elevation of a typical thread-advancing thread store device which may be employed to advantage in the apparatus of the present invention, the section being along line 3—3 of Figure 4; and Figure 4 is an end elevation of the thread-advancing thread store device of Figure 3. Corresponding parts bear corresponding reference characters.

While for convenience the apparatus of the illustrated embodiment of the invention exemplifies the collection of thread in the form of a spool package, it is not intended thereby to limit the scope or spirit of the invention.

Referring now to the apparatus shown in Figures 1 and 2, the thread 1 is formed in the usual manner by extrusion of viscose from the spinneret 2 into a sulphuric acid coagulating bath 3 which is contained in trough 4 of a conventional spool-spinning machine. In machines of this type there are a plurality of units disposed along a common bath trough, each consisting of a spin-

neret and its corresponding collecting spool; however, for clarity only one such unit is shown. The viscose for each spinneret is supplied through pipe 5 and mass tube 6 from a suitable source such as a supply line and pump (not shown). A guide 7 is preferably provided to guide the thread 1 from the spinneret 2 onto a unitary thread-advancing thread store device 8 shown as completely submerged in the bath.

On thread-advancing thread store device 8 the thread 1 is subjected for a relatively long period of time to the action of the bath. This is done by temporarily storing a predetermined length thereof in a plurality of spaced substantially helical turns which are formed and advanced axially along the device by the motion of its elements during rotation. The thread 1 is discharged or otherwise taken off the device and then passes to the collecting spool 9 through its associated traverse guide 10. It is desirable to provide a guide 11 to prevent any tangling of the thread at the discharge end of the device which may be caused by the motion of the traverse guide 10 of the spool 9, as illustrated by the extreme positions 10' of the guide 10 and corresponding positions 11' of the thread. In Figures 1 and 2 are shown guides 7 and 11 of suitable design, the operation of which will be explained more in detail hereinafter.

Thread-advancing thread store device 8 may be of any suitable form by which the thread, by the action of the elements of the device, may be continuously but temporarily stored in the form of an advancing generally circular helix. The device, for instance, may take the form of a thread-advancing reel such as that illustrated in Figures 3 and 4. This reel is of substantially the same form and operates in substantially the same manner as that shown, described and claimed in an application entitled "Winding reel," Serial No. 652,089, filed January 16, 1933, by Walter F. Knebusch (Patent No. 2,210,914).

Referring to Figures 3 and 4, it can be seen that the reel is composed of two generally cylindrical members 12 and 13. Member 12, which may be termed the concentric member, is mounted on a drive shaft 14 with its axis concentric with that of the shaft 14, to which it is fixed for rotation by set screw 15. Its periphery is composed of bar-like portions 16 between which are slots 17. Member 13, which may be termed the eccentric member, is mounted with its axis offset from and inclined to that of member 12 and is composed of a spider 18 rigidly supporting bars 19, which are disposed in slots 17 of member 12. Member 13 may be provided with a bearing portion, such as a sleeve 21 rotatably mounted on the cylindrical bushing 22, which may be so formed and supported on the frame member 23 that its axis bears the aforesaid offset and inclined relationship with regard to shaft 14.

Rotation of the shaft 14, which may be journaled in member 22, thus causes the concentric reel member 12 to rotate. Eccentric reel member 13 is rotated by contact of its bars 19 with the bars 16 of member 12. The offset and inclined relationship of reel members 12 and 13 causes the thread to progress in spaced helical turns axially along the reel in a manner more fully explained in said application Serial No. 652,089. Any desired predetermined length of thread, within reasonable limits, may thus be continuously but temporarily stored on a thread-advancing reel. The illustrated reel, being sup-

ported at one end only, has a free end in the sense that its unsupported end is free of a projecting shaft or supporting means which might impede the discharge of thread, toward which free end the thread is advanced by the reel.

The reel shown, moreover, is self-threading because it is made up of two rotatable reel members the peripheries of which intersect. Therefore, after a thread has been started on the reel, further rotation of the reel will cause it to thread itself up, because the leading end of the thread cannot wind about one reel member only but must wind about both. These features provide great convenience in threading up or starting of the thread on the reel. As a result of the fact that it is supported from one end only, the reel may be said to be of cantilever construction.

It is obvious that various other forms of thread-advancing thread store devices might be used in lieu of the reel shown in Figures 3 and 4.

It has been found advantageous to provide means for adjusting the position of the reel so that it may be disposed entirely below the surface of, partly immersed in, or wholly out of the bath. It may, for example, be desired to operate the reel while disposed partly within and partly without the bath. It is more convenient for the operator, who can thus see while threading or starting the thread on the reel, to be able to move the reel to a position in which it is wholly out of the bath. Furthermore, when the reel is removed from the bath, it can thread itself up more readily than when disposed in the bath, wherein the liquid might wash the thread turns off the reel or entangle them during the threading up operation.

For the purpose of providing adjustability and adaptability to conventional spinning machines, as well as portability for the purpose of cleaning, repairing, etc., the apparatus may be constructed as shown in Figures 1 and 2. In this embodiment of the invention, reel drive shaft 14, by means of which the reel 8 is rotated, is positively driven by some means as a gear 24 which may be driven through idler 26 by a pinion 27 rigidly mounted on a drive shaft 28, as, for example, by pin 29. Suitable means, as an electric motor 31, may be provided to rotate the drive shaft 28. Motor 31 may be mounted in alignment with shaft 28 on a frame 32 extending over the trough wall 33 on the apron 34 of the spinning machine, which apron 34 may be sloped as shown to drain any liquids spilled on it to the waste trough 35.

Drive shaft 28 is journaled, as in bearing 36, in member 37 carried by frame 32, the upper portion of which member 37 may be curved as at 45 to provide a guide portion for the arm 38 mounted in the housing 39, in which is journaled drive shaft 28. Housing 39 is formed integral with or otherwise rigidly fastened to the frame member 23, which supports reel 8 and the gears that drive it from shaft 28, and is adapted to be swung about shaft 28 as an axis. Arm 38, which is rigidly mounted on the housing 39, bears a handle assembly 41 containing a spring 42 and plunger 43 by means of which the reel is held in the position corresponding to any of the holes 44 in the curved periphery 45 of the member 37. It is desirable to provide means such as roller 46, rotatably mounted on arm 38, and roller 47, rotatably mounted on the bracket 48, to support the load exerted by the weight of the reel 8 and its supporting and driv-

ing means which would otherwise tend to bend the drive shaft 28. A supporting bracket 49 may also be provided for this purpose. A housing 51 may be provided to shield the reel from any turbulence that might otherwise be set up by rotation of the gears.

The desirability of guiding the thread as it contacts and leaves the reel is just as great when the reel is swung to the various other previously mentioned positions as when it is wholly submerged. However, when the reel is disposed in these other positions, the thread contacts and leaves the reel at angular positions different from those at the lowermost reel position. This is illustrated by broken lines 1' of Figure 2, which indicate the angular positions of the thread with respect to the reel when the latter is in position 8' above the surface of the bath.

For these reasons the guides 7 and 11 may be of the design shown, in which they are curved and mounted on the housing 39, as by lugs 52 and 53, so that they bear the same relationship to the reel 8 in all positions. It will be observed that the guides perform their function throughout the entire range of positions of the reel. That is, as the points at which the thread contacts and leaves the reel change, and consequently the angular position of the thread with respect to the reel changes, due to the above-mentioned changes in position of the reel, the thread slides along each guide to the new position, as is illustrated by the position of the thread 1' with respect to the guides 7 and 11 corresponding to reel position 8' of Figure 2.

In the operation of apparatus of the character shown in Figures 1 and 2, the operator, by means of the adjusting handle 41, first swings the reel up and completely out of the bath to a position such as that indicated at 8' and starts the motor 31. He then seizes the end of the thread 1 formed by the mass issuing from the spinneret 2 disposed in coagulating bath 3, passes the thread through guide 7 and starts it on the reel 8 by winding it one or two turns around the reel. Because the thread is wet, it readily adheres to the reel bars. Because of the action of the reel as it rotates, the thread forms spaced helical turns on the reel which are advanced axially of the reel and finally discharged from the free end. The operator seizes the end of the thread as or after it discharges, leads it past guide 11 and starts it on the subsequent collecting or withdrawing device, in this case the spool 9 and traverse guide 10. The reel is then swung into the bath until it assumes the desired position, whether wholly or partly immersed.

The present invention makes possible the regulation of the depth of immersion of the reel in the bath, thus varying the degree of coagulation of the thread or the like with a minimum of inconvenience to the operator. As previously indicated, the adjustable mounting permits the complete removal of the reel from the coagulating bath for the purpose of starting the thread or the like upon the reel. After the thread or the like is wound upon the reel, the mounting may be adjusted to provide the desired period of submission of the thread to the action of the coagulating liquid. In addition to facilitating the threading up operation, the apparatus lends itself to use with any conventional type of spinning machine.

It is obvious that numerous changes may be made in the embodiment of the invention shown and described herein and that other embodiments

may be devised without departing in any way from the spirit of the invention. For instance, although in the illustrated embodiment of the invention the reel is shown as completely submerged in the bath, it may be so disposed that it is largely, but not entirely, immersed in the bath or even so disposed that it dips into the bath to only a very limited extent. Various methods of mounting and driving the reel may be employed in lieu of that shown; furthermore, the reel may be employed in association with various processing baths other than coagulating baths.

It is intended that the patent shall cover the features of novelty characterizing the invention, but no claim is made to the subject matter defined in the claims of Kline et al. application Serial No. 110,460 filed November 12, 1936.

What is claimed is:

- 20 1. Apparatus for handling thread or the like comprising a cantilever thread-advancing thread store device having a periphery of substantially circular cross section upon which the thread or the like is continuously but temporarily stored in a plurality of spaced, generally helical turns while being advanced toward the unsupported end of said thread-advancing thread store device, said device having its unsupported end unobstructed by anything impeding the discharge of thread or the like therefrom; a supporting member on which said thread-advancing thread store device is rotatably mounted from one end thereof; a drive shaft disposed with its axis outside the periphery of said thread-advancing thread store device; means for rotating said drive shaft; means for rotating said thread-advancing thread store device from said drive shaft; a frame carrying said drive shaft and said supporting member; means for adjusting said supporting member to a variety of positions about the axis of said drive shaft; and means holding said supporting member in any one of said variety of positions.
- 25 2. Apparatus for handling thread or the like comprising a unitary, self-threading thread-advancing thread store device upon which the thread or the like is continuously but temporarily stored in a plurality of spaced, generally helical turns; a supporting member on which said thread-advancing thread store device is rotatably mounted; a drive shaft mounted with its axis in spaced relation to said thread-advancing thread store device; means for rotating said drive shaft; means for rotating said thread-advancing thread store device from said drive shaft; a frame supporting said drive shaft and said supporting member; means for adjusting said supporting member about the axis of said drive shaft, whereby said thread-advancing thread store device while mounted upon said supporting member may be bodily moved to a variety of positions; and means for holding said supporting member in any one of said variety of positions.
- 30 3. Apparatus for handling thread or the like comprising a thread-advancing thread store device on which thread or the like is continuously but temporarily stored in a plurality of spaced, generally helical turns; a supporting member upon which said thread-advancing thread store device is rotatably mounted; rotatable driving means disposed with its axis of rotation in spaced relation to said thread-advancing thread store device; means for rotating said thread-advancing thread store device from said driving means; a frame carrying said rotatable driving means and said supporting member, said supporting

member being mounted independently of the source of the thread or the like; means for adjusting said supporting member about the axis of said rotatable driving means, whereby said thread-advancing thread store device while mounted upon said supporting member may be bodily moved to a variety of positions; and means for holding said supporting member in any one of said variety of positions.

4. Apparatus for handling thread or the like comprising a thread-advancing thread store device; a supporting member on which said thread-advancing thread store device is mounted; rotatable driving means disposed with its axis in spaced relation to said thread-advancing thread store device; means for rotating said thread-advancing thread store device from said driving means; a frame carrying said rotatable driving means and said supporting member; means for adjusting said supporting member with respect to said rotatable driving means, whereby said thread-advancing thread store device may be

bodily moved to a variety of positions; and means for holding said supporting member in any one of said variety of positions.

5. Apparatus of the character described in claim 4 in which said thread-advancing thread store device is a unitary self-threading device of cantilever construction adapted to advance the thread or the like toward the unsupported end thereof.

6. Apparatus for handling thread or the like comprising a unitary, self-threading thread-advancing thread store device of cantilever construction to which the thread or the like proceeds from its source, said device advancing the thread or the like toward the unsupported end thereof; means including a shaft for actuating said thread-advancing thread-store device; and, surrounding said shaft, means for adjustably supporting said thread-advancing thread store device so that the device as a whole is movable to a variety of positions.
